Patented Apr. 23, 1918.

Fig 1

UNITED STATES PATENT OFFICE.

JOHAN WALFRID OSTMAN AND CHARLES B. GOODWIN, OF WINNIPEG, MANITOBA,
CANADA.

WINDOW-SCREEN.

1,263,460.

Specification of Letters Patent. Patented Apr. 23, 1918.

Application filed September 27, 1916. Serial No. 122,512.

To all whom it may concern:

Be it known that we, JOHAN WALFRID OSTMAN and CHARLES B. GOODWIN, both of the city of Winnipeg, in the Province of Manitoba, Canada, have jointly invented certain new and useful Improvements in Window-Screens, of which the following is the specification.

The invention relates to improvements in window screens and the principal object of the invention is to provide a screen which can be inserted in the window frame and attached to the sash and will open and close with the sash when the same is raised and lowered.

A further object of the invention is to construct and arrange a roller screen so that it can be manufactured at small cost, can be readily applied on the various forms of existing windows and when applied is positive in action and effectively excludes insects and flies.

A still further object of the invention is to construct and arrange a roller screen such that it is weather proof and does not require to be removed unless desired in the winter time.

With the above objects in view the invention consists essentially in the arrangement and construction of parts hereinafter more particularly described and later pointed out in the appended claims, reference being had to the accompanying drawing in which:—

Figure 1 represents an exterior view of the device as applied on a window, parts being broken away to expose construction.

Fig. 2 represents a vertical sectional view through the screen and lower portion of the window frame sash with the sash closed.

Fig. 3 represents a vertical sectional view of a portion of the frame and sash with the screen open.

Fig. 4 represents a horizontal sectional view through the window frame and sash and looking downwardly toward the sill.

Fig. 5 represents an enlarged detailed vertical sectional view through the right hand end of the roller showing the method of fastening the spring.

Fig. 6 represents an end view of the roller.

Fig. 7 represents an enlarged detailed horizontal sectional view through the parting strip.

Fig. 8 represents a face view of the right hand spring strip.

55

Fig. 9 represents an enlarged detailed vertical sectional view through the perforated edging strip applied on the screen.

In the drawing like characters of reference indicate corresponding parts in the several figures.

1 represents a window frame of ordinary construction comprising side members 2 and 3 erected on the sill 4, the side members embodying upright facing boards 5 and 6 and inserted intervening boards 7, the inner edges of the facing boards being positioned so that they extend beyond the inserted boards and form the outer guides 8 and 9 for the window sashes.

70

Parting strips 10 and 11 are located centrally between the guides 8 and 9 being carried by the board 7 of the side members of the frame.

All of these parts are of ordinary construction and as our invention is attached to the inner sash 12 of the frame this alone is shown. As is customary, it operates in the grooves or slides formed by the parting strips and inner guides 9. In the lower ends of the grooves or slides we locate opposing spring strips or hangers 13 and 14 which have their upper ends permanently fastened by screws 15 to the frame and have their lower ends bent slightly inwardly and provided, one with a slot shown at 16 and the other with a rounded hole 17, the slot and hole being horizontally opposite. The frame is notched away at 19 behind the hanger 13 to allow the same to be pressed in when it is desired, to remove the roller later described. The two hangers carry the spring roller 20 which is constructed and arranged as now described.

90

One end of the roller is supplied with an extending pin or stub axle 21 which is received within the opening 17 and the other end thereof is cored out as shown at 22 and contains a coiled spring 23 spiraled around a spindle 24 which has the inner end thereof rotatably mounted in a carrying plate 25 secured to the roller and the outer end thereof flattened as indicated at 26 and protruding through a cap plate 27 permanently secured to the end of the roller.

100

A collar 28 is provided on the spindle to

105

prevent it from shifting to the right and the inner end of the spring is fastened to the spindle while the outer end is secured to the cap 27. The flattened end of the 5 spindle is received within the slot 16 of the hanger 14.

From the above arrangement and mounting it will be obvious that when the roller is turned in one direction the spring will be 10 tightened or coiled with the result that when the roller is released it will return back to the original position, the spring un-coiling.

To the roller we secure the inner end of 15 a strip of wire netting 29 which is approximately the full width of the frame and has the upper edge thereof fitted with an edging strip 30 supplied at suitable intervals with perforations 31 by means of which the 20 edge of the strip can be fastened to the lowermost cross member 12' of the sash by means of hooks 32 supplied on the cross member.

In order to accommodate the roller of the 25 screen the lower ends of the parting strips are cut short of the sill as shown at 33 and the inner faces of both of the parting strips are longitudinally grooved or channeled at 34 to receive the edges of the screen which, 30 it will be understood, extend beyond the edging strip and into the grooves.

In order to render the roller screen weather proof we have provided a housing or casing 35 on the sill and a guard 36 on 35 the sash which coöperate when the sash is closed to entirely inclose the roller screen. The casing is actually a strip of sheet metal passing the full width of the frame and having the lower edge flanged and fastened at 40 37 to the sill, the body portion thereof slightly rounded to conform to the roller and the upper edge terminating in a position such that it will pass behind the edge of the guard 36 when the sash is closed.

45 From the above description it will be seen that this device can be readily applied on the various types of existing window frames and when applied can remain as a fixture as when closed the casing and guard effect- 50 tively protect the screen against the weather. It can however, be readily taken out by removing the guard and then pressing in the spring hanger 13 to release the roller. Once

the roller is taken out the edging strip can be raised from the hook and the complete 55 screen stored till required for further use.

What we claim as our invention is:—

1. The combination with a window frame and a sash vertically slidable in the frame, of a spring constrained roller, offset spring 60 straps suspending the roller from the frame in a location adjacent the frame sill and a screen attached to and wound on the roller and having the free end thereof secured to the sash.

2. The combination with a window frame and a sash vertically slidable in the frame, of a spring constrained roller removably mounted in the lower portion of the frame and adjacent the frame sill, a screen secured 70 to and wound on the roller, means detachably fastening the free edge of the screen to the lower part of the sash, and means detachably fastening the roller to the sash.

3. The combination with a window frame 75 and a sash vertically slidable in the frame, of a pair of oppositely disposed depressible hangers located on the sides of the frame and adjacent the frame sill, a spring constrained roller mounted in the hangers, a screen attached to and wound on the roller and extending between the sides of the frame and means removably fastening the free edge of the screen to the lowermost portion of the sash, comprising a perforated 80 edging strip carried by the screen and hooks on the sash co-acting with the perforations.

4. The combination with a window frame, a sash slidably mounted in the frame and a spring constrained roller screen carried by 90 the frame adjacent the sill and attached to the sash and adapted to open and close in the raising and closing of the sash, of a housing secured to the sill and passing between the side members of the frame and 95 covering the roller screen and a guard carried by the sash and co-acting with the casing in the closed position of the sash.

Signed at Winnipeg this 30th day of August, 1916.

JOHAN WALFRID OSTMAN.
CHARLES B. GOODWIN.

In the presence of—

G. S. ROXBURGH,
ROLAND FOSTER.
